UNITED STATES PATENT OFFICE.

VICTOR F. L. PALM, OF MASCOT, TENNESSEE, ASSIGNOR OF ONE-HALF TO HENRY C. KARLSON, OF HASBROUCK HEIGHTS, NEW JERSEY.

WRENCH.

Application filed January 18, 1919. Serial No. 270,865.

To all whom it may concern:

Be it known that I, VICTOR F. L. PALM, a citizen of Sweden, and a resident of Mascot, in the county of Knox and State of Tennessee, have invented certain new and useful Improvements in Wrenches, of which the following is a specification.

This invention relates to improvements in adjustable wrenches, and embodies special features of construction that enable it to be used as a combined monkey and ratchet wrench.

One of the objects of the invention is to produce an improved device of the nature set forth capable of being adjustably applied to nuts or bolt-heads of various sizes, or other articles of that class, in such a manner that they may be turned either continuously or intermittently at option, without removing the tool from the article in any case or shifting it from side to side there-around, as is done with wrenches of ordinary description.

Another object is the production of a device of the character described that will firmly seize a nut or its equivalent, either to tighten or loosen the same, when turned in one direction, but will automatically slip by one corner of the nut when swung in the opposite direction, so as to enable it to take hold on different sides thereof to complete the tightening or loosening, as the case may be, thus permitting the wrench to be used in quarters that are cramped and admit only of giving it a partial rotary movement at a time.

A further object is to provide a device of the species mentioned with means for locking the self-adjusting mechanism thereof so that the device can be used as an ordinary monkey-wrench, in either direction.

A still further object is the provision of a device of the class referred to consisting of but a small number of elements, of simple and durable construction, readily assembled or disassembled either for repairs or for replacement of worn-out parts, and amenable to low cost of production.

Other objects and advantages of the invention will become apparent as the specification proceeds.

With the aforesaid objects in view, the invention consists of the novel combinations

and arrangements of parts hereinafter described in their preferred embodiments, 55 pointed out in the subjoined claims, and illustrated on the annexed drawings, wherein like parts are designated by the same reference characters thruout the several views.

60 In the drawings:—

Figure I is a front edge view of a wrench embodying one form of the invention;

Fig. II is a sectional side elevation of the same form;

Fig. III is a side elevation similar to the preceding view except that certain parts are in changed position, and others broken away or omitted;

Fig. IV is a rear edge view of the same 70 form of the improved wrench;

Fig. V is a transverse section on the line V—V of Fig. II, looking downward, in the direction pointed out by the arrows;

Fig. VI is a plan view showing the under-side of a structural detail included in the said Fig. II;

Fig. VII is a partial front elevation of the structure shown in the view next following;

Fig. VIII is a side elevation of the upper part of a wrench embodying a modified form of the invention;

Fig. IX is a view similar to Fig. VIII, with certain parts in a changed position; 85

Fig. X is an edge view of the same modification, looking from the left-hand side of Fig. XI;

Fig. XI is a side elevation of the upper half of another wrench of modified form, 90 certain parts thereof appearing in section, and others being omitted; and

Fig. XII is a similar elevation of the latter-named form, with parts thereof in a changed position.

The various forms of the invention disclosed herein all include a fixed jaw 1, which may be at the head of the wrench as shown, and a plurality of guide members 2 and 3, extending therefrom to the opposite extremity of the implement. These members are sufficiently spaced apart to receive between them a pair of slid-able elements 4 and 5, provided with forwardly-projected wings 6 and 7 constituting therewith a sliding carrier. External flanges 8 and 9, on the side

of the slideable elements remote from the wings thereof, engage the rear edges of the said guide members, while the front edges of the latter are in contact with shoulders 10 5 and 11, formed at the juncture of the said elements and their said wings. Preferably and as shown, the lower edges of the slideable elements are made to run straight or at right angles to the transverse dimension of the 10 guide members, whereas their upper edges are inclined downwardly and forwardly, for a purpose that will be duly explained hereinafter.

A relatively stationary or non-rotatable 15 nut 14 is placed intermediate of the wings 6 and 7, and this nut has a rear extension 15, which is received between the paired elements 4 and 5, the latter being suitably spaced apart by means of shouldered studs 20 17. The nut 14 and its extension 15 are rigidly secured by rivets 18, to the elements 4, 5, and wings 6, 7, respectively. A translating screw 19, with a knurled head 20, engages the non-rotatable nut so as to impart 25 to it a reciprocating movement alongside and in front of the guides 2 and 3, between which is located a keeper 22, having a forwardly-extending bottom ledge 23, adapted to take the thrust from the said screw. An 30 upper ledge 24, slightly projecting also from the front of the keeper, serves to retain the head 20 thereon. The keeper is secured, as by rivets 26, to the parallel guides 2 and 3.

Below the keeper aforesaid is the wrench 35 handle, which as indicated in Figs. I to IV may include a hand-piece 29, made of wood or other suitable material, and inserted between the lower ends of the side guides 2 and 3. Rivets 30 afford a simple and reliable means of fastening the hand-piece to 40 the guides.

Directly under the fixed jaw 1, and co-acting therewith, is a movable jaw 33. The latter-named jaw has curtain walls 34 and 45 35, projecting rearwardly from the opposite sides thereof, and a centrally disposed rib 36. The curtain walls are received between the wings 6 and 7, while the rib is lodged intermediately of the slideable elements 4 and 5, and designed to tilt together with said 50 walls downwardly outward within the guides 2 and 3. At the outer end of the rib is a rearwardly overhung nose portion or hook 37, and in the under side of the rib is formed 55 a recess 38, from which depends an anchoring lug 39. Guide-pins 40 and 41 are further provided on the said rib, the same projecting sidewise therefrom and being adapted to slide through longitudinal slots 44, in 60 the slideable elements 4 and 5. These slots have offset portions or obliquely extending notches 45 and 46, at the rear side of each, in which the said pins 40 and 41 operate.

An angular pin 47, preferably square in 65 cross-section, is set transversely of the slid-

able elements 4 and 5, and serves as an anchorage for the lower end of a vertically disposed leaf-spring 48, the upper end of which is attached to an ear 49, depending from the rib 36, of the movable jaw, previously mentioned. The spring 48 may be in the nature of a flat clock-spring, and when properly arranged will act to hold the ear 49 rearwardly. This spring, however, is not considered as an indispensable feature of the 75 invention, which may work satisfactorily without its use.

Co-acting ledges 50 and 51 are formed, respectively, at the under side of the said movable jaw 33, in the rear portion thereof, and upon the shoulders 10, 11, intermediate of the elements 4, 5, and wings 6, 7. These ledges constitute a sliding fulcrum for the movable jaw, permitting it to tilt downwardly between the said wings under the 80 fixed jaw. Normally, however, the movable jaw is urged upward by a helical coil-spring 52, anchored at its lower end to a pin 53, upon the nut 14, and connected at its upper end to the lug 39, within the recess 38, before mentioned as formed in the under side of the rib 36.

Ears 56, projecting forwardly from the wing portions 6 and 7 of the slide elements 4 and 5, provide a support for a transversely disposed pin 57, to which is hinged a small door or flap 58, designed to shield the helical spring aforesaid, by covering the gap between the said wing portions where this spring is located. The flap 58 is attached 100 at its lower end to the hinge-pin, and at the upper end laps over an apron 59, extending downwardly from the movable jaw 33. A flat spring 60, the opposite extremities of which are respectively secured to the upper 105 face of the nut 14 and to a rivet or pin 61 in the center of the flap, operates to draw in the latter against the apron and thus to keep it tightly closed.

A slide 64 is arranged so as to take under the hook or nose portion 37 of the rib 36, and by engaging the said hook or nose portion serves to lock the jaw 33 against tilting movement, when this is not wanted. The said slide has inwardly turned sides 65 and 66, taking over the opposite edges of the flanges 8 and 9, of the elements 4 and 5, as shown clearly in Fig. V. The flanges 8 and 9, it will be observed, are suitably bevelled at the edges for this purpose. An outwardly-extending lip 67, on the slide 64, affords a hold for the operator's fingers in manipulating it, and a slit 68, made longitudinally of the slide, imparts the necessary resilience to its said sides 65 and 66, with relation to the flanges engaged thereby. Stop lugs 69 are further provided at the rear of the said flanges 8 and 9, to limit the downward travel of the slide 64, when disengaged and pulled away from the said hook or nose 130

portion. It will be noted that a pair of these stops is provided so as to insure perfect working of the slide, though it is conceivable that a single stop would be sufficient 5 to gain the end in view.

When the jaws 1 and 33 of the wrench are adjusted to grasp the object to be turned, for instance a nut of given size, as A in Fig. II, and the slide 64 is disengaged from 10 the said hook 37, any strain exerted upon the nut at the point indicated by the arrow B, incidentally to tightening the same, causes the before described ledges 50 and 15 51, of the movable jaw and adjacent wing portions of the slideable elements, to come into or keep in close contact with one another, and the upper guide-pins 40 to slide into or remain in the outermost extremities 20 of the notches 45 of the slots 44. This occurs every time that force is applied to operate the wrench by moving the handle 29 thereof in the direction pointed out by the arrow C. On the other hand, when the handle 29 is pushed back in the reverse direction, as represented by the arrow D in Fig. 25 III, the pressure upon the movable jaw 33 causes it to yield and slip by the lower inner corner of the nut, which then assumes the position denoted by A¹ relatively to the wrench in the latter-named figure. At that 30 time, the ledges 50 of the movable jaw 33 slide off the co-acting ledges 51 of the wings 6 and 7, and the helical coil-spring 52 is depressed, as illustrated. In the meantime 35 also the pins 40 move into the angles formed at the junction of each slot 44 with its offset or side notch 45, while the spring 48 tends to push back the ear 49 of the rib 36, so that the pins 41 will ride on the lower 40 edges of the lower notches or offsets 46 of the said slots 44. As soon as the momentarily parted jaws of the wrench have passed the opposite corners of the nut, as appearing at A¹, Fig. III, the movable jaw 45 33 springs upward again to its former position, and the combined fixed and movable jaws embrace new sides of the nut, with the same conditions prevailing as shown in Fig. II. But, if the slide 64 is allowed to remain 50 in engagement with the hook 37, the jaw 33 is locked from movement in either direction, and the implement can then be used as an ordinary monkey-wrench.

Figs. VII, VIII, and IX represent a 55 modification of the invention involving a few changes in the construction hereinbefore described. Thus, for example, the wings 6 and 7 may be formed with front or outside shoulders 10^a, which may be arranged to meet along a central line, as indicated in Fig. VII. This would strengthen the implement transversely, and further provide a sufficient closure over the space where the spring 52 is situated. A straight, 60 flat spring 48^a can also be employed, in lieu

of the clock spring previously mentioned, for holding up the rear end of the rib 36 of the movable jaw 33. A spring like 48^a may be anchored at one end in the rear extension 15 of the non-rotatable nut 14, and 70 at its other end may engage a keeper, as 49^a, extending rearwardly from the rib 36. The upper end of the spring 48^a, it will be understood, would slide through the keeper during displacement of the movable jaw. 75 A further alteration in the structure may consist in providing ledges both rearward and forward, as at 50^a and 51^a, for the movable jaw, the same co-acting with similar ledges 50^b and 51^b, on the wings 6 and 7. 80 The movable jaw in this modification does not oscillate, but moves forwardly and downwardly, as clearly indicated by the changes of position outlined in Figs. VIII and IX. 85

Further changes of construction are illustrated in Figs. X, XI and XII, which give another modified exemplification of the invention. As shown in the views last named, the rib 36 of the movable jaw 33 may be 90 equipped with a single set of guide-pins 40^a, one projecting from each side of the rib. These pins are arranged to move in single slots 45^a, disposed obliquely in opposite portions of the slideable elements 4 and 5. 95 Again, the co-acting ledges may be formed as at 50^a and 51^a, on the underside of the movable jaw 33, at the inner corner thereof, and upon the shoulders 10 and 11 of the wings 6 and 7, respectively. Farther down 100 in front, a tie 60^a may be utilized for attaching the door or flap 58 to the helical spring 52. The tie, it will be perceived, furnishes a simple and effective means of holding the flap up to the apron 59. Recesses 72 and 73 are provided in addition inside the shoulders 10, 11, and the said ledges 50^a, and within these recesses are seated the heads of a link 74, controlling the oscillation of the movable jaw 33. A clearance opening 75 is made in the rib 36 to insure for this link all necessary freedom of movement. 110

While certain preferred embodiments of this device have been shown and described, 115 it will be understood that changes in the form, arrangements, proportions, sizes and details thereof may be made, without departing from the scope of the invention as defined by the appended claims. 120

Having described my invention what I desire to secure by Letters Patent and claim, is:—

1. A wrench of the type specified including a relatively fixed jaw, guiding means 125 comprising spaced elements extending therefrom, a carrier translatable along said means, a movable jaw having a shiftable fulcrum upon said carrier enabling it to be tilted downwardly under said fixed jaw, a 130

member on said movable jaw extending rearwardly between and beyond the inner edges of the guiding means, and a pin and slot connection coupling said member to the carrier at a distance from the inner edges of the said guiding means.

2. A wrench of the type specified including guides, a fixed jaw thereon, a carrier translatable on said guides, a movable jaw having a shiftable fulcrum upon said carrier enabling it to be tilted downwardly under said fixed jaw, an arm extending rearwardly from said movable jaw beyond the inner edges of the guides, means located between the inner and outer edges of the said guides affording a loose connection between said arm and the carrier, and a spring intermediate of the arm and the movable jaw tending to restore the latter to normal position.

3. A wrench of the type specified including a guide, a jaw fixed thereon, a carrier translatable on said guide, a movable jaw mounted at the upper part of said carrier in position to tilt downwardly under said fixed jaw, a spring located intermediate the lower part of the carrier and said movable jaw tending to restore the latter to normal position, and a closure extending over the space between the movable jaw and the lower part of the carrier, said closure being flexibly connected to the carrier so as to partake of the movements of the latter named jaw while serving to shield said spring.

4. A wrench of the type specified including a guide, a jaw fixed thereon, a carrier translatable with relation to said jaw along said guide, said carrier extending forwardly of the guide and having its upper surface inclined downwardly therefrom under the fixed jaw, and a movable jaw arranged to be tilted upon the carrier approximately to the plane of said surface so as to clear the corners of an article held between the said jaws during reverse movement.

5. A wrench of the type specified including a pair of guides, a fixed jaw thereon, a carrier translatable along said guides toward and away from said jaw, a movable jaw having an extension flexibly connected to said carrier between the guides, and a shiftable fulcrum between said movable jaw and its said extension enabling the former to be tilted downwardly under the first named jaw.

6. A wrench of the type specified including a guide, a carrier translatable along the same, a tiltable jaw on said carrier, a rearward extension on said jaw, a loose connection between the carrier and said extension enabling the jaw to tilt automatically during the backward stroke of said guide, and means on the carrier capable of locking or unlocking the jaw through engagement with the extension, whereby the wrench may be

adapted for use either continuously or intermittently at option.

7. A wrench of the type specified including a guide, a carrier translatable on said guide, a nut translatable with said carrier, an outwardly tiltable jaw having a sliding fulcrum on the latter, flexible means connecting said jaw to the carrier in a plane above said nut, and resilient means arranged to bear upon the jaw both forwardly and rearwardly of its fulcrum so as normally to maintain the jaw in its operative positions.

8. A wrench of the type specified including guiding means, a jaw fixed at one end thereof, a carrier formed with a ledge and translatable on said means, a tiltable jaw having a rear extension and slidably fulcrumed on said ledge, a spring urging said tiltable jaw to its seat on the ledge, and flexible means consisting of a pin and slot connection holding said extension to the rear part of said carrier in such a manner as to permit the latter named jaw to slide off its fulcrum and incline outwardly when the wrench is moved in one direction and to be subsequently returned to its seat by the action of said spring while the wrench moves oppositely.

9. A wrench of the type specified including a guide, a relatively fixed jaw thereon, a carrier provided with a ledge and translatable on said guide, said carrier having a slot in its rear portion, a tiltable jaw formed with an extension projecting rearwardly beside the carrier, said tiltable jaw being slidably fulcrumed on said ledge, a projection engaging said slot from said extension, and a spring serving to press the latter named jaw against its seat on the ledge, the arrangement being such that when the wrench is moved in one direction the tiltable jaw slides off its fulcrum while said projection advances in its slot, but during reverse movement of the wrench the tiltable jaw resumes its seat and the projection is restored to its original position.

10. A wrench of the type specified including a guiding means, a fixed jaw at one end thereof, a carrier formed with a forward downwardly inclined ledge and translatable on said means, said carrier being provided in its rear portion with a slot having a laterally offset notch, a tiltable jaw with a rear extension beside the carrier, a pin on said extension adapted alternately to engage said notch and said slot, said tiltable jaw having a bevelled part slidably fulcrumed on said ledge, and a spring urging said part to its seat, the above mentioned elements being so constructed and arranged that when a downward strain is exerted upon the latter named jaw it is resisted by a binding action occurring between the bevelled part, the seat therefor, and said pin lodged in the notch, but if an outward pressure be applied substantially in

the direction of the seat's surface it will cause the bevelled part to slide off its fulcrum on the ledge and the pin to move into the slot, thereby permitting the jaw to become 5 tilted.

11. A wrench of the type specified including a guide, a fixed jaw at one end thereof, a carrier composed of two parts translatable on said guide, each of said parts having an 10 inclined ledge, a tiltable jaw provided with bevelled portions slidably fulcrumed upon the ledges of said carrier, a rearwardly extending rib on said tiltable jaw, a pin and slot connection between the carrier and said 15 rib permitting tilting of the latter named jaw, a spring functioned to urge said bevelled portions against their seats on said ledges, and a slide mounted on the rear edges of the carrier in position to lock the corre-

sponding end of the rib so as to hold the tilt- 20 able jaw immovable.

12. A wrench of the type specified includ- 25 ing parallel guides, a handle at one end of the latter, a jaw fixed to the other extremity of the same, a carrier independent of said handle and said jaw translatable between the last named parts along said guides, said car- 30 rier being composed of elements engaging the guides at their inner sides, a movable jaw tiltable downwardly under the fixed jaw 35 from the carrier, a member of narrower width than said movable jaw extending rear- wardly therefrom in interposed relation to the said elements, and a connection loosely coupling said member to the elements of the carrier intermediate the front and rear edges of the guides.

VICTOR F. L. PALM.
